US00D978358S

(12) **United States Design Patent** (10) **Patent No.:** **US D978,358 S**
(45) **Date of Patent:** **** Feb. 14, 2023**

(54) **UROFLOWMETER**

- (71) Applicant: **CLEARTRAC TECHNOLOGIES, LLC**, Elizabethton, TN (US)
- (72) Inventors: **Brent Laing**, Greenwood Village, CO (US); **John Green**, Elizabethton, TN (US); **Paul R. Johnson**, Boulder, CO (US); **Robert John Smith**, Louisville, CO (US); **Robert Edwin Schneider**, Erie, CO (US); **Magnus Hargis**, Hudson, CO (US); **Elise Geolat Edson**, Boulder, CO (US); **Elizabeth A. O'Brien**, Louisville, CO (US)
- (73) Assignee: **CLEARTRAC TECHNOLOGIES, LLC**, Elizabethton, TN (US)
- (**) Term: **15 Years**
- (21) Appl. No.: **29/810,290**
- (22) Filed: **Oct. 4, 2021**

Related U.S. Application Data

- (63) Continuation of application No. 29/656,567, filed on Jul. 13, 2018, now Pat. No. Des. 932,632.
- (51) **LOC (14) Cl.** **24-02**

CLAIM

The ornamental design for a uroflowmeter, as shown and described.

DESCRIPTION

FIG. 1 shows a front perspective view of a uroflowmeter; FIG. 2 shows a rear perspective view of the uroflowmeter of FIG. 1; FIG. 3 shows a right elevation view of the uroflowmeter of FIG. 1; FIG. 4 shows a left elevation view of the uroflowmeter of FIG. 1; FIG. 5 shows a front elevation view of the uroflowmeter of FIG. 1; FIG. 6 shows a rear elevation view of the uroflowmeter of FIG. 1; FIG. 7 shows a top view of the piece of the uroflowmeter of FIG. 1; and, FIG. 8 shows a bottom view of the uroflowmeter of FIG. 1. The broken lines in FIGS. 1-8 illustrate portions of the uroflowmeter and form no part of the claimed design.

1 Claim, 4 Drawing Sheets
